UNITED STATES PATENT OFFICE.

JAMES B. GOCKE, OF LOS ANGELES, AND CHARLES A. WILSON, OF TORRANCE,
CALIFORNIA.

SPLIT SPIDER FOR OIL-WELL CASINGS AND THE LIKE.

Application filed April 2, 1924. Serial No. 703,631.

To all whom it may concern:

Be it known that we, JAMES B. GOCKE and CHARLES A. WILSON, citizens of the United States, residing at Los Angeles and Torrance, in the county of Los Angeles and State of California, have invented new and useful Improvements in Split Spiders for Oil-Well Casings and the like, of which the following is a specification.

10 Our invention relates to split spiders for oil well casings and the like, and consists of the novel features herein shown, described and claimed.

An object is to make a spider in two pieces for use in carrying slips, in raising and lowering drill stems, flow pipes, pump tubing, and the like, and which may be readily separated and removed laterally from the stem or cable passing through it.

20 Other objects and advantages will appear from the drawings and specification.

The drawings illustrate the invention.

Figure 1 is a perspective showing the top of one piece and the bottom of the other piece, the two pieces ready to go together to form a split spider, in accordance with the principles of our invention.

Fig. 2 is a top plan view upon a reduced scale and showing the two pieces of the spider assembled and fastened together by bails and ready for use, parts being broken away and shown in section.

Fig. 3 is a side elevation looking in the direction indicated by the arrow 3 in Fig. 2.

Fig. 4 is a side elevation looking in the direction indicated by the arrow 4 in Fig. 2.

The details of the split spider shown in the drawings are as follows.

40 The split spider comprises the lower part 1 and the upper part 2. The lower part 1 has a straight flat lower face 3 with a vertical opening 4 at one side of its vertical axis, the opening 4 being half round. A notch 5 is formed from one side of the lower part and extends to the vertical faces 6 and 7, said faces being in a longitudinal line diametrical of the completed opening. Flanges 8 and 9 extend 45 upwardly in longitudinal alignment at opposite sides of the notch 5, there being supporting blocks having flat faces 10 and 11 parallel with the lower face 3 at corresponding sides of the flanges 8 and 9. A half bearing block 12 extends upwardly

from the face 3 and connects the material forming the faces 10 and 11, the opening 4 being formed in the inner side of the bearing block 12. Vertical pillars 13 and 14 extend outwardly from the ends of the bearing block 12 toward the faces 10 and 11 and parallel with the flanges 8 and 9. The bearing block 12 is the full height of the assembled spider.

The upper part 2 has a bearing block 15 fitting in the notch 5 and having a half round vertical axial opening 16 uniting with the opening 4 to make a slip bearing. Blocks 17 and 18 extend from the ends of the block 15 and have recesses 19 and 20 to receive the flanges 8 and 9 and have vertical recesses 21 and 22 to receive the pillars 13 and 14 and the lower upper supporting blocks have faces 23 and 24 which are parallel with the lower face 25 of the block 15, so that when the face 25 is level and forms a part of the face 3, the faces 23 and 24 fit upon the faces 10 and 11.

The flanges 8 and 9 fitting in the recesses 19 and 20 and the pillars 13 and 14 fitting in the recesses 21 and 22 hold the bearing blocks 12 and 15 together, and when the parts 1 and 2 have been assembled bolts 26 and 27 are inserted through the ends of the bails 28 and 29 and through the blocks 17 and 18 above the faces 23 and 24 and through the flanges 8 and 9, thereby securely connecting the parts 1 and 2 together to form a spider for holding slips and to be operated in the usual way.

When a stem such as a drill stem or a cable is extending through the completed slip opening 30, formed by the half openings 4 and 16, the spider may be readily removed laterally by removing the bolts 26 and 27 and lifting the part 2 upwardly relative to the part 1.

Various changes may be made without departing from the spirit of our invention as claimed.

We claim:

1. A split spider having in combination complementary half bearing blocks, vertical pillars on one of said blocks to engage in recesses on the other block, straight faces on each of said blocks adapted to contact, and flanges on the first of said half bearing blocks engaging recesses on the other bearing block.

2. A split spider comprising a lower part having a half bearing block with a half round portion, pillars on the edge of said half bearing block, flat faces at one end of said half bearing block and extending sideways therefrom, a complementary half bearing block having a half round opening, recesses adjacent the edge of the block to engage the said pillars, and faces secured to the outer edge of the half bearing block and adapted to contact with the flat faces first mentioned.
3. A split spider as claimed in claim 2 having flanges on the flat faces of the lower bearing block adapted to engage recesses on the flat faces of the complementary bearing block.
4. A split spider having in combination a lower part having a half bearing block with a half round portion, flat members extending from each side of the half bearing block and from one end thereof, flanges on said members, a complementary half bearing block having a half round portion, flat members extending from opposite sides thereof and adapted to engage the flat members of the lower bearing block, and recesses therein adapted to engage the flanges on the lower bearing block.
5. A spider comprising two half bearing blocks, overlapping blocks extending from the bearing blocks and carrying inter-locking means to resist movement crosswise of the axis and adapted to be assembled and separated by a movement longitudinal of

the axis, bails spanning the ends of the assembled spider, and bolts inserted through the ends of the bails and through the spider.

6. A split spider comprising a lower part and an upper part, there being a half bearing block on the lower part and a half bearing block on the upper part, said bearing blocks fitting together on a diametrical plane and forming a vertical opening, there being lower supporting blocks extending from the lower part of the first half bearing block and corresponding upper blocks extending from the second half bearing block and fitting upon the lower supporting blocks, and there being vertical pillars extending outwardly from the ends of the first bearing block above the lower supporting blocks and there being flanges extending upwardly from the lower supporting blocks, and there being vertical recesses in the upper supporting blocks to receive the vertical pillars and there being recesses in the upper supporting blocks to receive the vertical flanges, so that the upper part will match with the lower part upon a downward movement of the upper part to a level with the lower part, and so that the upper part cannot pass downwardly below the lower part, and so that the two parts cannot separate on a line crosswise of the axis of the vertical opening.

In testimony whereof we have signed our names to this specification.

JAMES B. GOCKE.
CHARLES A. WILSON.
